SINK DIVIDER MAT

Maurice H. Kraines, 4078 Monteith Drive, Los Angeles, Calif., and Robert L. Unkrich, Long Beach, Calif.; said Unkrich assignor to said Kraines

Filed Dec. 26, 1961, Ser. No. 68,053

Term of patent 14 years

(Cl. D9—6)

Fig. 1

FIG. 2 is a rear elevational view of said mat; and

FIG. 3 is an end view of said mat.

We claim:

The ornamental design for a sink divider mat, substantially as shown.
